*Primary Examiner—Stella Reid**Attorney, Agent, or Firm—Roylance, Abrams, Berdo & Goodman***[57] CLAIM**

The ornamental design for a gum massager, as shown and described.

DESCRIPTION

FIG. 1 is a front elevational view of a gum massager showing my new design;

FIG. 2 is a rear elevational view thereof;

FIG. 3 is a right side elevational view thereof;

FIG. 4 is a left side elevational view thereof;

FIG. 5 is a front end elevational view thereof;

FIG. 6 is rear end elevational view thereof;

FIG. 7 is a second embodiment of the gum massager, with only difference residing in the shape of the nodules on the base support and all other portions being identical to that shown in FIGS. 2-6; and.

FIG. 8 is a front elevational view thereof.
